UNITED STATES PATENT OFFICE.

WILLIAM C. SCHULZE, OF CHICAGO, ILLINOIS.

ABDOMINAL EXERCISER.

1,064,093.

Specification of Letters Patent. Patented June 10, 1913.

Application filed July 25, 1910. Serial No. 573,664.

To all whom it may concern:

Be it known that I, WILLIAM C. SCHULZE, a citizen of the United States of America, and a resident of Chicago, county of Cook, 5 State of Illinois, have invented certain new and useful Improvements in Abdominal Exercisers, of which the following is a specification.

The main objects of this invention are to 10 provide an improved abdominal exerciser to manipulate, massage, knead, and percuss the abdomen for the purpose of inducing muscular activity and peristaltic action in the intestines; to provide improved means 15 for actuating the working parts in such a manner as to be the exciting cause of the movement as normally carried on in the human body; to provide improved means for increasing the action on the abdomen at 20 certain predetermined positions; and to provide an improved, simple, and substantial construction capable of withstanding all stresses of ordinary usage.

A specific structure embodying this invention is illustrated in the accompanying drawings, in which:

Figure 1 is a sectional view of the abdominal exerciser, partly in elevation, on the plane of the drive shaft. Fig. 2 is a detail of the slidable raised track which may be used to increase the action of the hinged traveling ball. Figs. 3 and 4 show in detail the adjustable hangers for supporting the casing. Fig. 5 is a sketch showing the 35 apparatus as applied to the patient. Fig. 6 is a sectional view, partly broken away, showing the rotating mechanism and the adjustable ball accelerators in position.

In the construction shown, the flexible 40 diaphragm 1 is the top member of a casing 2 which forms a housing for a rotatable spider 3. On the bottom member of the casing 2 is secured a base plate 4 and a fixed shaft 5, on which is mounted the rotatable 45 spider 3. The driving mechanism consists of a driven bevel gear 6 secured to the spider 3, which meshes with the driving bevel gear 7, which is in turn pinned to the drive shaft 8. The drive shaft 8 is supported on a bearing 9 fastened to the base 50 plate 4, and the casing 2 forms an outer bearing where the drive shaft passes through the casing at 10. The outer end of the drive shaft 8 has a coupling 11 which 55 is threaded on the shaft and is adapted to receive a threaded extension shaft 12. The

rotatable spider 3 has arms 13, 14, 15, and 16, of different lengths, each carrying a shaft 17 mounted in a plane parallel to the diaphragm 1. On each of the four shafts is 60 rotatably mounted the ball 18, which keeps the diaphragm 1 under stress at the point of contact and establishes stress lines on the flexible medium or diaphragm connecting the points of contact of the various balls. 65 When the spider 3 is actuated by turning the crank shaft 12, there is produced on the diaphragm 1 a progressive wave motion which is capable of transmission to the human abdomen. The form of the wave 70 front of the motion is substantially a spiral with four centers starting near the center and increasing in velocity toward the outside.

For convenience in application, the device is sometimes hung on the back of an ordinary chair, as shown in Fig. 5, and a pair of hangers, comprising a pair of adjustable hooks 19, 19, pass through the fittings 20, 20 which are fastened to the casing 2, and thumbscrews 21, 21 serve to lock the hanger hooks 19, 19 in place. There are two positions on the abdomen where percussion action is especially desired. These two points are both approximated by the 85 travel of the ball 18 on the longest arm 16 of the rotating spider 3, and provision is made for increased stress on the diaphragm at and near these points by providing a long axis 17 for the ball 18 on the arm 16. Two 90 lugs 22, 22, serve as guides to prevent side motion of the axis, and two lugs 23, 23 engage a pivot 24 which passes through the long axis 17. To increase the stress on the diaphragm at the desired points, two adjustable wedge-shaped blocks 25 and 26 are 95 slidably fastened to the base of the casing 2. A projecting arm 27 is connected to the inclined block 25 and projects through the casing in such a manner as to permit the 100 movement of the inclined track 25 into or out of the path of the outer ball 18. In a similar manner, the projecting arm 28 controls the position of the inclined track 26. When the track engages the ball, it is deflected toward the diaphragm and produces an increased stress or percussion on the diaphragm at the point immediately 105 above the wedge-shaped block.

In operation, the diaphragm 1 of the device is placed so as to press on the abdomen, the operating crank handle 12 being on the

right-hand side of the patient. The operating crank handle is arranged to turn fast when turned right-handed, and to turn loose and be separable when turned left-handed.

5 When the handle 12 is turned right-handed, the bevel gears 6 and 7 will turn the rotating spider 3 and the rotatable balls 18 in a left-handed direction. The balls pressing against the diaphragm will produce points 10 and lines of stress on the surface of the diaphragm, with an action which will be comparatively slow at the center and increasing to the outer edge. When it is desired to accelerate the percussion at either 15 the sigmoid flexure or at the cæcal valve or both, then the inclined track or tracks are placed in position so as to elevate the ball 18 which is mounted on the spider arm 16. If increased action is desired over the sigmoid flexure, the projecting arm 27 is pushed 20 into the casing, forcing the inclined track 25 in such a position that it will engage the outer ball 18. If increased action is desired over the cæcal valve, the inclined block 26 25 is placed in the path of the outer ball 18 by pushing the projecting arm 28 to the position as shown in Fig. 6.

It is especially desirable, in the treatment of intestinal inactivity, to induce muscular 30 and peristaltic action in the intestines in the direction and with the magnitude of the action as it is normally carried on in the body. In this invention, a comparatively gentle, clockwise, kneading action is imparted to 35 the center of the abdomen, with a stronger action across the upper part of the abdomen from right to left, and from the upper left-hand side of the abdomen toward the sigmoid flexure, and from the sigmoid flexure 40 toward the cæcal valve. Properly located accelerators 25 and 26 are provided to produce the strongest percussion action over the sigmoid flexure, and over the cæcal valve. The operating crank handle 12 is 45 made non-reversible, so that the exerciser always works in the right direction.

Although but one specific embodiment of this invention is herein shown and described, it will be understood that numerous 50 details of the construction shown may be altered or omitted without departing from the spirit of this invention, as defined by the following claims.

I claim:

1. In an abdominal exerciser, a mechanism 55 comprising a plurality of rotatably mounted balls and unsupported therebetween, a diaphragm stretched over said balls, said diaphragm being adapted to transmit to the abdomen an irregular wave motion actuated 60 by said balls, and non-reversible means operative to actuate said mechanism.

2. A device of the class described, comprising a casing, means for suspending said casing, a diaphragm member for said casing, a mechanism housed in said casing and rotating on an axis perpendicular to said diaphragm, pressing parts of said mechanism rotatably mounted on axes substantially parallel to said diaphragm, means connected to said device and operative to actuate said mechanism, and manually controlled means for relatively increasing the action of one or more of the pressing parts 70 at predetermined points.

3. In an abdominal exerciser, a mechanism comprising a plurality of surfaces movable in concentric paths, a flexible medium stretched over said surfaces in a manner to cause stress lines therein between the 80 points of contact with said surfaces, and means for moving said surfaces to cause a progressive movement of said stress lines.

4. In an abdominal exerciser, a mechanism comprising a plurality of surfaces 85 movable in concentric paths, a flexible medium stretched over said surfaces in a manner to cause stress lines therein between the points of contact with said surfaces, means for moving said surfaces to cause a progressive movement of said stress lines, and means for increasing the stress upon said medium at certain desired points.

5. In an abdominal exerciser, a mechanism comprising a plurality of bodies having rounded surfaces movable in concentric paths, means for actuating said bodies, and means for causing at will one or more of said bodies to depart from the normal plane 95 of rotation at predetermined points.

Signed at Chicago this 18th day of July 100
1910.

WILLIAM C. SCHULZE.
